UNITED STATES PATENT OFFICE.

GEORGE B. STOCKING, OF TACOMA, WASHINGTON.

DESIGN FOR A SPOON, &c.

SPECIFICATION forming part of Design No. 22,060, dated December 20, 1892.

Application filed November 23, 1892. Serial No. 452,955. Term of patent 7 years.

To all whom it may concern:

Be it known that I, GEORGE B. STOCKING, a citizen of the United States, residing at Tacoma, in the county of Pierce and State of Washington, have invented and produced a new and original Design for a Spoon or other Similar Article, of which the following is a description, reference being had to the accompanying drawing, forming a part thereof, which represents a plan view of a spoon exhibiting my design.

The leading feature of my design is the representation of a rhododendron flower forming the outline of a portion of the handle of the spoon.

A is a panel inclosed by a scroll like margin

at its ends and sides, the sides merging into and forming a part of the handle, from the upper end of which the leaves and stems of a rhododendron flower appear to proceed, the outline of the flower extending into and becoming the outline of the handle. 20

What I claim is:

The design for a spoon substantially as shown and described. 25

In testimony whereof I hereunto affix my signature in presence of two witnesses.

GEORGE B. STOCKING.

Witnesses:

JAMES GARVEY,
R. C. VROOMAN.
